(57) **CLAIM**

The ornamental design for slippers, as shown and described.

DESCRIPTION

FIG. 1 is a top view of slippers, showing my new design; FIG. 2 is a front, top and right perspective view of the left slipper;

FIG. 3 is a rear, bottom and right perspective thereof;

FIG. 4 is a top view thereof;

FIG. 5 is a bottom view thereof;

FIG. 6 is a left side view thereof;

FIG. 7 is a right side view thereof;

FIG. 8 is a rear view thereof;

FIG. 9 is a front view thereof;

FIG. 10 is an enlarged view of the area labeled "10" in FIG. 3;

FIG. 11 is a front, top and right perspective view of the right slipper;

FIG. 12 is a rear, bottom and right perspective thereof;

FIG. 13 is a top view thereof;

FIG. 14 is a bottom view thereof;

FIG. 15 is a left side view thereof;

FIG. 16 is a right side view thereof;

FIG. 17 is a rear view thereof;

FIG. 18 is a front view thereof; and,

FIG. 19 is an enlarged view of the area labeled "19" in FIG. 12.

The dot-dash lines in FIGS. 3, 10, 12, and 19 are for the purpose of showing the areas of enlargement and form no part of the claimed design.

1 Claim, 19 Drawing Sheets
